UNITED STATES PATENT OFFICE.

DAVID W. R. MORGAN, OF SWARTHMORE, PENNSYLVANIA, ASSIGNOR TO WESTINGHOUSE ELECTRIC & MANUFACTURING COMPANY, A CORPORATION OF PENNSYLVANIA.

SCOOP CONDENSER.

Application filed October 28, 1927. Serial No. 229,503.

My invention relates to scoop condensers, and it has for an object to provide means for improving the circulating system for this class of equipment.

In condensers of the type described, the cooling media is usually delivered to the condenser by means of scoops which open axially into the water boxes, the pressure head required to pass the circulating media through the tubes being developed by the speed of the vessel. Stand-by pumps are sometimes provided for producing the necessary head when the speed of the vessel is not sufficient to develop it. However, the arrangement of scoops is such that whether the pressure head be developed by the speed of the vessel or partially by a stand-by pump, the cooling media is not equally distributed to the tubes, and adequate flow through the outer rows of tubes is not obtained. This is particularly objectionable in the tubes adjacent the steam inlet, where the temperature of the condensable gases is the highest, for the flow of circulating media through these tubes on the inlet side of the nest is not always adequate to effect a proper transfer of heat, and, in some cases, the circulating media is sufficiently heated to be transformed into steam. This condition is obviously unsatisfactory, for it causes such circulating media, as remains in the tubes, to pass back and forth, and the steam also issues from the tubes and forms steam pockets in the water boxes and seriously interferes with the operation of the condenser.

More particularly, therefore, an object of my invention is to provide means for more equally distributing the flow of circulating media, especially through the outer tubes of the nest, and to provide for an adequate flow through the tubes on the inlet side of the condenser.

Another object is to provide means for intermittently utilizing the available pressure head for passing cooling media through a portion of the nest of cooling tubes and, in the event that full circulation is required, for translating cooling media through the remaining portion of the nest.

A further object is to provide means for automatically controlling a circulating system of the type described.

Apparatus embodying the features of my invention is shown in the accompanying

drawings forming a part of this application, in which:

Fig. 1 is an elevation of a marine power installation equipped with an automatic control system for controlling the flow of circulating media through a surface condenser; 60

Fig. 2 is a sectional view of a throttle valve;

Fig. 3 is a fragmentary view of a turbine; and,

Figs. 4 and 5 are similar to Fig. 1, but show modified forms of my invention.

According to my invention a guide vane is pivotally mounted in some suitable position, as on a tube sheet in the inlet water box. This vane is adapted, in its normal position, to deflect a portion of the main stream of circulating media toward the tubes on the inlet side of the nest, and in this way to insure an adequate flow through these tubes. The vane is also adapted to close off a portion of the nest, as for example, the inlet side of the nest so that when operating under light loads the circulating media may be directed through only a portion of the nest in which case the pressure head, due to the progress of the vessel, may be adequate to produce the proper flow even at reduced speeds. Fluid translating means are also provided, such for example, as a propeller pump, for translating cooling media through a portion of the nest while the scoop action is effective to pass the cooling media through the remaining portion of the nest.

My invention also contemplates the provision of means for automatically producing these desired effects in response to either the conditions of temperature and pressure within the condenser or in response to condenser pressure and to pressure in a stage of the turbine.

Referring now to the drawing for a better understanding of my invention, I show, in Fig. 1, a turbine 10 and a scoop condenser 11, which is provided with a suitable inlet scoop 13, an inlet water box 14, a discharge water box 16 and a discharge scoop 17.

Pivotedly mounted in the inlet water box 14, as on the tube sheet 18, is a guide vane 19, and similarly disposed in the water box 16 is a guide vane 21. These vanes are, preferably, arranged to be inclined away from the condenser steam inlet, as shown,

and to project slightly into the scoops 13 and 17, respectively, so as to divide the main stream of circulating media passing therethrough and to deflect the proper amount 5 of this stream toward the tubes in the inlet side of the nest, and particularly toward the outermost rows of these tubes. In this way it is assured that, whether the vessel be proceeding ahead or astern, an adequate flow 10 will be maintained through the outermost tubes on the inlet side of the nest provided the motion of the vessel is sufficient to produce this flow.

However, at reduced speeds and also when 15 running astern, it is frequently necessary to provide some form of fluid translating means to assist the flow of circulating media through the nest. I provide for such conditions by mounting the propeller pump 22 20 in the passage 23, which communicates with the forward scoop 13 and with the water box 14. At such times as the motion of the vessel is inadequate to produce the proper flow through the entire nest, the vane 19 25 may be swung against the abutment 24, provided in the scoop 13, so as to close off the tubes on the inlet side of the nest from the incoming stream of circulating media and to direct this entire stream through the remaining portion of the nest. The pump 22 30 is then operated to pass circulating media from the scoop 13 through the passage 23, the water box 14 and the tubes on the inlet side of the nest. Thus, the action of the scoop is rendered more effective, for the pressure head developed is utilized in passing the cooling media through only a portion 35 of the nest, while the auxiliary pump 22 is utilized to pass circulating media 40 through the remaining portion.

It may also occur that the turbine 10 may 45 be operating at a relatively light load, in which case the entire condensing surface would not be necessary, and under these conditions it would be possible to produce the proper vacuum in the condenser by passing circulating media through only a portion 50 of the cooling tubes. Should these conditions occur, the vanes 19 and 21 would be raised, or closed, so that the vane 19 would 55 be swung against the abutment 24 and the vane 21 would be swung against the abutment 26, thus closing off a portion of the nest on the inlet side of the same and directing the main stream of circulating media through the remaining portion of the nest of cooling tubes.

Any suitable means may be provided for 60 operating the vanes 19 and 21, but preferably pressure-responsive devices, such as the fluid relays 27 and 28, are provided for this purpose. These relays are similar in all respects and hence, a description of either 65 will be adequate.

The relay 27 comprises a working cylin-

der 29 having therein a piston 31 which is connected by means of its rod 32 and the link 33 to the vane 19. The pilot valve 34 for controlling the piston 31 comprises a spool type piston valve 36, which is urged 70 by the spring 37 into a position to admit any suitable fluid under pressure through the port 38 and the valve housing and through the connection 39 to the upper side of the piston 31 in the working cylinder 29, and 75 to permit fluid to be discharged from the cylinder 29, on the rod side of the piston 31, through the connection 41, and the valve housing and the discharge port 42. In case the pilot valve 36 is moved to its other extreme 80 position, it will be obvious that the reverse operation will take place, and that fluid will be exhausted from the cylinder 29 through the connection 39 and the discharge port 43, the piston 31 being actuated 85 by the pressure of the fluid acting through the connection 41 and on the rod side of the piston 31, in which case the vane 19 would be swung against the abutment 24 in the forward scoop 13.

While any suitable means may be provided for actuating the pump 22, I preferably provide, either an electric motor, or a suitable turbine. In the form shown I have provided an electric motor 44. In order that 95 the electric motor 44 may be automatically brought into play to operate the pump 22 at the proper time, I provide an electrical control system comprising the positive bus bar 45 and the negative bus bar 46, and I 100 connect the motor 44 with the positive side of the line through the connection 47, a snap switch 48 and the connection 49. The negative lead from the motor 44 is connected with the negative bus bar 46 and comprises 105 the connection 52, the solenoid 53 and the connection 54.

From the connection 54, the negative lead from the motor 44 is divided into parallel circuits which are rendered alternately effective by the gravity switch 56. As shown, the gravity switch 56 completes the circuit from the connection 54 to the connection 57, through the solenoid 58 and connection 59 to the negative bus bar 46. When the gravity switch 56 is in its uppermost position it completes the circuit from the connection 54, through the connections 61 and 62 to the negative bus bar 46.

The solenoids 53 and 58 are arranged to 120 actuate the pilot valves of the fluid-pressure relays 27 and 28 respectively, the pilot valves being held in their upper positions when the solenoids are energized. It will be apparent, therefore, that when the gravity switch 56 125 is in its lower position, both solenoids 53 and 58 will be energized and both relays 27 and 28 will operate to raise the vanes 19 and 21, respectively. On the other hand, when the gravity switch 56 is in its upper position, 130

only the solenoid 53 will be energized and consequently, only the vane 19 will be raised.

The snap switch 48 is connected with an expansible bellows 63, which is adapted to be actuated by a suitable fluid in the connection 64, which leads to a closed vessel (not shown) within the condenser. The characteristics of this fluid are such that when the proper conditions of temperature and pressure exist within the condenser, the volume of the fluid will permit the bellows 63 to contract and thus the snap switch 48 will be held in an open position by the spring 66, in which case the motor 44 cannot actuate the pump 22. However, should the vacuum fall off in the condenser, this would be accompanied by an increase in temperature which would expand the bellows 63 so as to close the snap 48 and actuate the motor 44.

To preclude the possibility of having the vane 21 swing against the abutment 26 in the aft scoop 17 while the motor 44 is operating, I provide a solenoid 67 for controlling the gravity switch 56. This solenoid 67 is shunted across the terminals of the motor by means of the connections 68 and 69, respectively. Hence, whenever the motor 44 is operating, the solenoid 67 will be energized and will hold the gravity switch in its upper position, wherein it will complete the circuit between the connections 61 and 62 to the negative bus, while the circuit to the solenoid 58 will be open at the gravity switch 56. It will thus be seen that the arrangement thus far described is adapted to automatically control the pump 22 from conditions of temperature and pressure existing within the condenser.

In order to provide for obtaining an improved circulation through the cooling surface required for condensing steam exhausted during periods of relatively light load, I provide means for rendering a portion of the cooling surface ineffective and rely upon the scoop action to pass circulating media through the active portion of the condensing apparatus. I accomplish this by swinging the vane 19 against the abutment 24 in the forward scoop 13 and by swinging the vane 21 against the abutment 26 in the aft scoop 17 so as to render the inlet side of the nest inactive and to pass the main stream of circulating media through the lower position of the nest of cooling tubes. This objective is attained by actuating the pressure-responsive devices 27 and 28, by means of the solenoids 53 and 58, to close the vanes 19 and 21.

That this may be done without interfering with the operation of the control system previously described, I provide a connection 71 between the positive bus 45 and a switch 72. An expansible bellows 73, similar to the bellows 63, is connected to the switch 72 and by means of the tube 74 with

a closed vessel 76 in one of the stages of the turbine 10. The fluid in the vessel 76 has characteristics which will cause the bellows 73 to be sufficiently expanded, while the turbine is under normal load, to maintain the switch 72 in an open position. However, should the load be decreased on the turbine, the corresponding drop in pressure and temperature will cause the fluid in the vessel 76 to permit the bellows 73 to contract, and this will permit the spring 77 to force the switch 72 into a closed position and will permit current to pass from the positive side of the line through the connections 78 and 52 to energize the solenoid 53, and thence to pass through the connection 54 across the contacts of the gravity switch 56 to energize the solenoid 58 from whence it returns to the negative side of the line through the connection 59. It will be observed in this case, that both solenoids 53 and 58 are energized and hence actuate the respective pilot valves 36 to raise the pistons and close the vanes 19 and 21, respectively. It will also be observed that the circuit from the positive side of the line is through the connection 71, switch 72, connections 78 and 52, and that the motor circuit is open at the switch 48, so that the motor will not be affected.

From the apparatus thus far described, it will be apparent that the fluid contained in the vessel 76 in the turbine need have only such characteristics as will cause it to contract on a decrease in temperature and as this decrease, which would occur in a stage of the turbine, will be quite an appreciable one; the range of temperature over which the desired decrease in volume of this fluid may take place is quite large. Likewise, the fluid which actuates the bellows 63 might only have such characteristics as will cause it to expand on an increase in temperature above that corresponding to the desired vacuum in the condenser. It will readily be seen, therefore, that by this system of dual control, the fluids employed for actuating the bellows 63 and 73 respectively, need have definite characteristics at only one point on the temperature scale, instead of at two points, as would be the case if only one fluid were used, and hence, many fluids are suitable for this purpose.

While there are many advantages of this dual control system, I prefer to have the conditions of temperature and pressure within the condenser dominate my control system. This is desirable so that, should the circulation of cooling media decrease in the condenser, and at the same time the load on the turbine be decreased, the vacuum would still be maintained in the condenser. Considering this aspect of my invention, it will be apparent that, should the snap switch 48 and the switch 72 be

closed at the same time, the motor 44 would operate as usual, the gravity switch 56 being actuated by the shunt circuit 68, 69, the current from the motor and from the switch 72 would pass to the negative bus through the connection 52, the solenoid 53, and the connections 54, 61 and 62. Thus, it is assured that the operating conditions of the turbine will not interfere with the maintenance of proper vacuum in the condenser.

The apparatus shown in Fig. 1 may be readily adapted to a turbine-driven pump as well as to a motor-driven pump. In case a turbine-driven pump were to be used, a throttle valve 79, such as shown in Fig. 2, might be used to control the turbine.

From Fig. 2 it will be seen that the valve 79 is normally held on its seat by spring 81, and that this valve may be opened by energizing the solenoid 82. To substitute a turbine-driven pump for the motor unit 44, it would merely be necessary, therefore, to connect the solenoid 82 to the connections 49 and 52 in Fig. 1, so that instead of having a current through these connections actuate a motor, it would energize the solenoid 82 and open the throttle valve to operate a turbine (not shown).

The apparatus shown in Fig. 4 differs from that previously described in that motors 44, pumps 22 and passages 23 are provided for each end of the condenser, and means are provided for rendering either pump effective, the controlling system being responsive to the conditions of temperature and pressure existing only in the condenser.

The apparatus, for rendering either of the pumps effective, here takes the form of gravity switches 91 and 92, which are adapted to ride on cams 93 and 94, respectively, of the cam shaft 96. A handwheel 97 is provided for rotating the cam shaft to reverse, or otherwise adjust the positions of the switches 91 and 92. The cams 93 and 94 are shown as being 180° apart, although, obviously, any suitable arrangement may be employed for this purpose, it merely being necessary to raise one of the gravity switches and to permit the other to drop at the same time.

As shown, the switches are in position to cut out the motor 44' and to actuate the motor 44, the circuit from the positive side of the line being through the connection 98, the two-way switch 99 to either of the contacts 101 or 102, the expansible bellows 63 being connected to the two-way switch and to the condenser in a manner similar to that in which it is connected to the snap switch 48, in Fig. 1.

Should the vacuum tend to fall off in the condenser, the corresponding rise in temperature would cause the bellows 63 to expand and to close the circuit through the

switch 99, the connection 101, to the contact 103 and across the gravity switch to the contact 104, through the connection 106 to the motor 44 to energize the same. The current would pass from the motor through connections 107, 108 and 109 to energize the solenoid 53 to actuate the pressure-responsive device 27 to close the vane 19. Simultaneously with the passage of the current through the motor, the shunt circuit 110 and 111, which is across the terminals of the motor, would energize the solenoid 112 to raise the gravity switch 113. It will thus be observed that after passing through the motor 44 and through the solenoid 53, the current would pass through the connection 114, across the gravity switch 116, through the connections 117 and 118, across the gravity switch 113 and through the connections 119 and 121, to the negative side 85 of the line, the gravity switch 113 being in its upper position and thus preventing the solenoid 58 from being energized.

The vane 21 would, therefore, remain open while the vane 19 would be closed and the pump 22 would be operated to pass circulating media through the inlet side of the nest until such time as the proper vacuum should be restored. Once the proper vacuum is again obtained, the bellows 63 would contract, being urged somewhat by the spring 122 acting on the two-way switch 99, and the circuit of the motor 44 would be opened at the switch 99.

Should the load on the turbine decrease to such an extent as to permit the condenser to produce a better vacuum than would be deemed necessary or expedient, the bellows 63 would contract so as to close the circuit between the positive side of the line, the connection 98, the two-way switch 99, contact 102, the connection 123, across the gravity switch 91 to contact 124, through the connections 108 and 109, the solenoid 53, the connection 114, across the gravity switch 116, through the connection 117 and across the gravity switch 113, which is now in its lower position, through the connection 126, the solenoid 58 and back to the negative side of the line through the connection 127, 115 across the gravity switch 92 and through the connection 128. In this instance, it will be noted that the motor circuit for the motor 44 is open at the contact 101 and the two-way switch 99, and consequently, neither 120 the motor, nor the solenoid 112, would be affected.

In order to render motor 44 ineffective and the motor 44' effective, the handwheel 97 is rotated to reverse the position of the gravity switches 91 and 92 by changing the position of the cams 93 and 94, respectively. In this position the gravity switch 91 will leave the circuit open across the contacts 103 and 104, 123 and 124, and will complete 130

the circuit between the connection 129 from the negative bus 46 and the connection 109. The gravity switch 92 will leave the circuit open between the connections 127 and 5 128, and will complete the circuit between the connections 131 and 132, and between the connections 133 and 134, respectively.

Should the vacuum fall off, the expansion of the bellows 63 will then complete the 10 circuit from the positive side of the line through the connection 98, the two-way switch 99, the connection 131 across the gravity switch 92 to the connection 132 to the motor 44'. Current would then pass 15 from the motor 44' through the connections 134, 136 and 127 to energize the solenoid 58, the gravity switch 92 now being in a position to break the circuit between the connections 127 and 128, 131 and 132, 20 respectively, and the switch 99 being in a position to break the circuit between the connections 133 and 98, respectively.

Simultaneously with the passage of current through the motor 44' the solenoid 137, 25 which is shunted across the terminals of the motor by the connections 138 and 139, would be energized to raise the gravity switch 116 to its upper position. Hence, the current would pass from the solenoid 58 through the 30 connection 126, across the gravity switch 113, which is now in its lower position, through the connections 117 and 141, across the gravity switch 116, through the connections 119 and 121 to the negative bus bar 46, 35 the circuit to the solenoid 53 being open at the gravity switch 116, and thus, assuring that the solenoid 53 will not be energized.

Should the vacuum in the condenser decrease below the requisite value, for any reason, as a decrease in the load on the turbine, 40 the bellows 63 would contract and the circuit from the positive side of the line would be closed through the connection 98, the two-way switch 99, the connection 133, across the gravity switch 92 to the connections 134, 136 45 and 127 to the solenoid 58, through the connection 126 across the gravity switch 113, the connection 117, the gravity switch 116 and through the connection 114, the solenoid 53, the connection 109 and across the gravity switch 91 to the negative side of the line 50 through the connection 129.

It will also be observed that in this condition, the circuit for the motor 44' is open 55 between the connection 131 and the switch 99. Likewise, the circuit for the motor 44 is open between the contact 101 and the switch 99. Hence, neither the motor 44', nor the motor 44 will be operated.

60 The apparatus shown in Fig. 5 is also provided with two pumps 22, 22', and the operating motors 44, 44', and the pumping units and the vanes 19 and 21 are arranged to function in the same manner as in Fig. 4, 65 but the control system is made responsive to

conditions of temperature and pressure existing in the turbine and in the condenser, as in Fig. 1. While this, in effect, is substantially a dual control system, the interrelation between these systems is such that that 70 portion of the system, which is directly responsive to the conditions in the condenser, will dominate the whole system in a manner similar to that described with reference to Fig. 1. 75

Considering the apparatus shown in Fig. 5, it will be clear that, when the vacuum falls off in the condenser, the resulting expansion of the bellows 63 will throw the switch 99 to complete the circuit from the 80 positive bus 45, through the connection 98 and the switch 99 to the contact 101, through this connection to the contact 103 and across the gravity switch 151 to the contact 104 and through the connection 106 to the motor 85 44. From the motor the current passes through the connection 152 to the solenoid 53, and then through the connection 114 across the gravity switch 116, through the connections 117 and 118. The solenoid 112 90 having been energized by the shunt circuit 110, 111, the gravity switch 113 is now in its upper position and hence, will complete the circuit from the connection 118 to the connections 119 and 121 to the negative bus 95 bar 46. In this way the motor 44 and the pump 22 are brought into play and the vane 19 is raised whenever there is an appreciable falling off of the vacuum in the condenser.

Now assume that the switch 99 remains 100 open and that a decrease in load on the turbine permits the bellows 73 to contract a sufficient amount to allow the spring 77 to throw the switch 72 and thus, to complete the circuit from the positive bus bar 45, 105 through the connection 71 and the switch 72 to the connection 153. The gravity switch 151 completes the circuit between the connections 153 and 154, and between the connections 154 and 156, so that current passes 110 from the latter through the connection 152 to the solenoid 53.

It will be observed here that the motor circuit is broken at the contact 101 and the switch 99. Hence the motor 44 will not be 115 operated, nor will the shunt circuit and the solenoid 112 be effective to raise the gravity switch 113. Thus the gravity switches 116 and 113, both being in their lower positions, will complete the circuit between the connections 114, 117 and 126 so that the current 120 may pass directly from the solenoid 53 to the solenoid 58.

From the solenoid 58, the current passes 125 through the connections 157 and 134, across the gravity switch 158, and through the connection 128 to the negative side of the line. It will be noted that the motor circuit is open between the connection 132 and the gravity switch 158 so that the motor 44' may 130

not be operated. In this manner, it is possible to operate both of the fluid relays 27 and 28 to raise the vanes 19 and 21 and thus, to cut the upper portion of the condenser 5 tube nest out of service. This assures flooding of all the active tubes and a better heat transfer than could otherwise be obtained at relatively low speeds where the scoop action is not fully effective.

10 The apparatus shown in Fig. 5 is intended to function in the manner just described when the scoop 13 is forward. However, the apparatus is so interconnected that the same results may be accomplished when proceeding 15 astern, in which case the scoop 17 would be effective to pass cooling water through the condenser. This is a very desirable feature, especially for high speed naval craft, for it assures improved performance of the condenser during maneuvers and like operations.

When proceeding astern, therefore, the handwheel 97 is rotated to reverse the position of the cams 93, 94 and of the gravity 25 switches 151 and 158. Assuming that, with the switches so reversed, the condenser pressure increases, then the bellows 63 will throw the switch 99 and complete the circuit from the positive bus bar 45 through the connection 98 and the switch 99 to the connection 131.

Being in its lower position, the gravity switch 158 will complete the circuit between the connections 131 and 132 to the motor 35 44'. From the motor 44', the current now passes through the connection 157 to the solenoid 58, and through the connection 126, across the gravity switch 113 to the connection 117.

40 The shunt circuit 138, 139, across the terminals of the motor 44', is now effective to energize the solenoid 137, so that the gravity switch 116 will be in its upper position. Hence, the current will pass from the connection 117, through the connection 141, across the gravity switch 116 and out to the negative side of the line through the connections 119 and 121. Thus, the motor 44' will be operated, and the vane 21 will be raised.

50 Now assume that the switch 99 remains open and that the switch 72 is closed. This completes the circuit from the positive side of the line through the connection 71, the switch 72, and the connections 153 and 159. The gravity switch 151, now being in its upper position, completes the circuit between the connections 159 and 161. Likewise, the gravity switch 158, being in its lower position, completes the circuit between the connections 161 and 162 so that current may pass on through the connections 55 60 157 to the solenoid 58.

From the connection 132, the circuit through the motor 44' is open between the

switch 99 and the connection 131. Hence, 65 the motor 44' will not operate and the shunt circuit 138, 139 will be ineffective, so that the gravity switch 116 will remain in its lower position. Thus, the current will pass directly, from the solenoid 58, through the connection 126, across the gravity switch 113, through the connection 117, across the gravity switch 116 and through the connection 114 to the solenoid 53. The current then passes from the solenoid 53, through 70 the connections 152, 156, across the gravity switch 151 and out to the negative side of the line through the connection 129. In this condition it will be observed that the circuit from the connection 152, through the motor 44 and the connection 106 is open between the contact 104 and the gravity switch 151. Hence, the motor 44 will remain ineffective.

75 In the event that both of the switches 72 and 99 are closed at the same time, it will be apparent that the shunt circuit 138, 139 from the motor 44' will energize the solenoid 137 and thus complete the circuit to the negative bus bar through the connection 121 and prevent the solenoid 53 from being energized. In this way it is assured that the vane 19 will never be closed while the condenser pressure is so high that it is necessary to operate the pump 22'. 80

85 While I have shown only the handwheel 97 for reversing the cams 93, 94 and the switches 151, 158, it will be obvious that this is merely representative of my invention and that suitable connections may be provided for effecting this reversal from some remote 90 station, as from the bridge of a ship. Likewise, various forms of reversing mechanism, other than the cams 93 and 94 may be employed.

95 While I have shown my invention in several forms it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended 100 claims.

115 What I claim is:

1. The combination with a scoop condenser, comprising a shell having an inlet, a nest of tubes within the shell, and scoops for passing circulating media through the nest, of directing means for deflecting a portion of the main stream of circulating media toward the outer tubes of the nest.

120 2. The combination with a scoop condenser, comprising a shell having an inlet, a nest of tubes within the shell, and scoops and water boxes for passing circulating media through the nest, of a vane in one water box and inclined away from the con- 125

denser inlet for deflecting a portion of the main stream of circulating media toward the outer tubes of the nest.

3. The combination with a scoop condenser, comprising a shell having an inlet, a nest of tubes within the shell, and scoops for passing circulating media through the nest, of a pivoted vane in the inlet scoop for directing a portion of circulating media 10 toward the outer tubes of the nest.

4. The combination with a scoop condenser, comprising a shell having an inlet, a nest of tubes within the shell, and scoops for passing circulating media through the nest, of means for directing all of the main stream of circulating media to tubes comprising a portion of the nest.

5. The combination with a scoop condenser, comprising a shell having an inlet, 20 a nest of tubes within the shell, and scoops for passing circulating media through the nest, of means in the inlet scoop for distributing the main stream of circulating media to the tubes adjacent the steam inlet 25 of the condenser.

6. The combination with a scoop condenser, comprising a shell having an inlet, a nest of tubes within the shell, and scoops for passing circulating media through the nest, 30 of means for either directing a portion of the main stream of circulating media toward one portion of the nest, or for directing substantially all of the main stream of circulating media to another portion of the nest.

35 7. The combination with a turbine and a scoop condenser comprising a shell having an inlet, a nest of tubes within the shell, and scoops for passing circulating media through the nest, of directing means for passing the main stream of circulating media through a portion of the nest, and means responsive to the load on the turbine for controlling the directing means.

45 8. The combination with a scoop condenser comprising a shell having an inlet, a nest of tubes within the shell, and scoops for passing circulating media through the nest, of directing means for passing the main stream of circulating media through a portion of the nest, fluid translating means for translating circulating media through another portion of the nest, and means responsive to the conditions of temperature and pressure within the condenser for concomitantly controlling 50 the directing means and the fluid translating means.

60 9. The combination with a turbine and a scoop condenser comprising a shell having an inlet, a nest of tubes within the shell, and scoops for passing circulating media through the nest, of a pivotal directing means adapted, in one position, to direct a portion of the main stream of circulating media toward an outer portion of the nest, and, in 65 another position, to pass the main stream of

circulating media through another portion of the nest, and means responsive to the load on the turbine for controlling the pivotal directing means.

10. The combination with a turbine and a scoop condenser comprising a shell having an inlet, a nest of tubes within the shell, and scoops for passing circulating media through the nest, of a pivotal directing means adapted in one position to direct a portion 70 of the main stream of circulating media to one portion of the nest and toward the outermost tubes of this portion, and in another position to direct the main stream of circulating media through another portion of the 75 nest, fluid translating means for translating circulating media through said one portion of the nest when the pivotal directing means is in said another position, means responsive to the load on the turbine for maintaining 80 the pivotal directing means in said one position while the turbine is under normal load and in said another position while the turbine is under a lighter load, and means responsive to the conditions of temperature 85 and pressure within the condenser for maintaining said pivotal directing means in said one position under normal conditions and in said another position under abnormal conditions and for actuating the fluid translating 90 means during the abnormal conditions.

11. The combination with a turbine and a scoop condenser comprising a shell having an inlet, a nest of tubes within the shell, and scoops for passing circulating media through the nest, of a pivotal directing means adapted in one position to direct a portion 100 of the main stream of circulating media to one portion of the nest and toward the outermost tubes of this one portion, and in another position to direct the main stream of circulating media through another portion of the nest, fluid translating means for translating circulating media through said one portion of the nest when the pivotal directing means is in said another position, means responsive to the load on the turbine for maintaining the pivotal directing means in said one position while the turbine is under 105 normal load and in said another position while the turbine is under a lighter load, and means responsive to the conditions of temperature and pressure within the condenser for maintaining said pivotal directing means in said one position under normal conditions 110 and in said another position under abnormal conditions and for actuating the fluid translating means during the abnormal conditions 115 irrespective of the load on the turbine.

120 In testimony whereof, I have hereunto subscribed my name this 17th day of October, 1927.
